(57) **CLAIM**

The ornamental design of a camera jib, as shown and described.

DESCRIPTION

FIG. 1 is a front elevation view of the camera jib;
 FIG. 2 is a back elevation view of the camera jib;
 FIG. 3 is a left side elevation view of the camera jib;
 FIG. 4 is a right side elevation view of the camera jib;
 FIG. 5 is a top plan view of the camera jib;
 FIG. 6 is a bottom plan view of the camera jib; and,
 FIG. 7 is a perspective view of the camera jib.
 The broken lines in FIGS. 1-7 setting forth additional portions
 of the camera jib depict environment only and form no part of
 the claimed design.
